OTHER PUBLICATIONS

U.S. Appl. No. 29/557,711, filed Mar. 11, 2016, of Formica et al., entitled: "Air Delivery Module and/or Components Thereof," (parent application).

(Continued)

Primary Examiner — Lilyana Bekic(74) *Attorney, Agent, or Firm* — Nixon & Vanderhye P.C.(57) **CLAIM**

The ornamental design for an air delivery module, as shown and described.

DESCRIPTION

FIG. 1 is a front perspective view of an air delivery module showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a rear perspective view thereof.

The broken lines in the drawings depict portions of the air delivery module that form no part of the claimed design.
